ADHESIVE ADVERTISING DISPLAY DEVICE

Philip G. Lux, Elkhart, Ind.

Application May 23, 1955, Serial No. 36,169

Term of patent 14 years

(Cl. D80—1)

FIG. 1.

Figure 1 is a side elevational view of an adhesive advertising display device, showing my new design; and
Figure 2 is a front elevational view thereof.

The dominant features of my design reside in the portions shown in full lines. The opposite side of the design is similar to the side shown in Figure 1 of the drawing.

I claim:

The ornamental design for an adhesive advertising display device, as shown and described.

FIG. 2.
